UNITED STATES PATENT OFFICE.

MICHAEL SIERSDORFER, OF LOUISVILLE, KENTUCKY.

CUTLERY POLISHER AND SHARPENER.

SPECIFICATION forming part of Letters Patent No. 428,321, dated May 20, 1890.

Application filed May 22, 1889. Serial No. 311,720. (No model.)

To all whom it may concern:

Be it known that I, MICHAEL SIERSDORFER, a citizen of the United States, residing at Louisville, county of Jefferson, State of Kentucky, 5 have invented a new and useful Combined Cutlery Sharpener and Polisher, of which the following is a specification.

My invention consists in certain improvements in details of construction of machines 10 for sharpening and polishing cutlery and the like, having for its object the rendering of such machines more complete and more conveniently operated.

Referring to the accompanying drawings, 15 which form a part of this specification, Figure 1 is a perspective view of my improved machine. Fig. 2 is a vertical transverse section on the line 2 2, Fig. 3. Fig. 3 is a vertical longitudinal section on the plane indicated by 20 line 3 3, Fig. 2. Fig. 4 is a horizontal sectional view in the plane of line 4 4, Fig. 3.

1 is the base-plate of the machine, and 2 2 are end frames having angular cut-away portions 3 3.

25 4 4' are the front plates bent to follow the edge of the cut-away portion of end plates 2. The upper front plate is also bent to form the top of the case of the machine.

5 is the rear plate, hinged at 6 to form a 30 door and held by catch 6'.

7 is a drawer to receive and enable the removal of powder and scourings.

8 8' are two wooden solid rollers covered 35 with a heavy layer of felt or other good polishing material. The trunnions of these rollers are mounted in boxes 9 9, which are guided in vertical slots in end plates 2 2 and are drawn toward each other by spiral tension-springs 10 10.

40 Upon the trunnions at one end of rollers 8 8' are pinions 11 11, meshing with a large gear 12, carried by a short shaft 13, also carried by one end plate of the casing. A suitable crank or hand wheel 14 on shaft 13 enables its operation, and motion is thereby transmitted to

45 rollers 8 8'. On placing a knife in the aperture between front plates 4 4' and pressing it

back and forth between the rollers while they are rotated the knife can be well polished. To provide equal pressure on the knife in opposite directions, so that it will not move either in or out except as forced to do so by the operator, the gear 12 engages the adjacent sides of pinions 11 11, turning them in the same direction.

55 That a good polishing-surface may be maintained on rollers 8 8', I provide in the top of the case a hopper 15, to be kept supplied with polishing-powder, which is fed therefrom to the surface of the upper roller. Upon the 60 trunnion of upper roller 8' opposite to pinions 11 11, I place a wheel 16, having faces of different diameters. Upon the larger is placed a heavy polishing-ring 17, of felt, for use on silver and other articles, and on the 65 smaller an emery-band 18, which may be employed for sharpening various articles preliminary to their polishing on felt ring 17.

A sponge-cup 19 is useful for wiping the 70 cutlery before placing it between the rollers 8 8' to be polished.

Clamps 20 serve for attaching the machine to a table or other support.

Having thus described my invention, the following is what I claim as new therein and 75 desire to secure by Letters Patent:

1. The combination of base-plate 1, end plates 2 2, curved front plates 4 4, extending from end plate to end plate and adapted to guide a knife-blade or other article between them, rollers 8 8', situated, respectively, above and below the inwardly-curved edges of the front plates, means for resiliently supporting said rollers, and operating mechanism, substantially as set forth.

80 2. The combination of a pair of polishing-rollers, curved plates in front of said rollers of greater length and curving between the rollers, and a hopper above the rollers for polishing-powder, substantially as set forth.

85 MICHAEL SIERSDORFER.

Witnesses:

EMILE DUPAQUIER,

FRANK SIERSDORFER.
